UNITED STATES PATENT OFFICE.

GEORGE R. MITCHELL, OF SYRACUSE, NEW YORK, ASSIGNOR OF ONE-THIRD TO JOHN WILLIAM SMITH AND ONE-THIRD TO ROBERT CROASDALE, BOTH OF SYRACUSE, NEW YORK.

PULVERIZER.

1,038,779.

Specification of Letters Patent. Patented Sept. 17, 1912.

Application filed November 8, 1910. Serial No. 591,325.

To all whom it may concern:

Be it known that I, GEORGE R. MITCHELL, of Syracuse, in the county of Onondaga, in the State of New York, have invented new and useful Improvements in Pulverizers, of which the following, taken in connection with the accompanying drawings, is a full, clear, and exact description.

This invention relates to certain improvements in pulverizers referred to in my pending application #591,324, filed November 8, 1910, and is adapted more particularly for reducing coal to a powdered condition for fuel which after initial ignition in a suitable burner or combustion chamber continues its combustion by converting the coal into gas and burning the gas by its own heat.

The main object is to render the operation of pulverizing the coal continuous but gradual under comparatively slow rotary action through the medium of separate concentric series of centrifugally operated hammers coacting with a corresponding series of concentric grids, the openings in which gradually diminish in size from the innermost to the outermost grids.

Another object is to provide one of the rotary elements with fan blades for forcibly expelling the coal powder from the coal pulverizer and if necessary forcing it into the combustion chamber of the furnace.

Other objects and uses will be brought out in the following description:

In the drawings Figure —1— is a longitudinal vertical sectional view of a coal pulverizer embodying the various features of my invention. Figs. —2— and —3— are transverse sectional views of the same pulverizer taken on lines 2—2 and 3—3 Fig. —1— but looking in opposite directions. Fig. 4 is a transverse sectional view through the hopper and feed screw taken on lines 4—4 Fig. 1, showing particularly the feed controlling gates.

This machine comprises a pair of coaxial disks —1— and —2— which are mounted respectively upon separate coaxial shaft sections —3— and —3'— and are provided respectively with a plurality of concentric circular grids 4, 5 and 6 and corresponding circular series of centrifugally operated hammers 7, 8 and 9 all of which parts are mounted

within a suitable inclosing case or housing —10—. The shaft sections 3 and 3' project outwardly through opposite ends of the case —10— and are provided with suitable bearings and separate pulleys —12— and —13— the pulley —12— serving to rotate the shaft —3— and disk —1— together with the circular grids mounted thereon in one direction while the pulley —13— serves to rotate the shaft section —3'— and corresponding disk —2— together with the hammers 7, 8 and 9 in the opposite direction. The disk —1— is provided with a central inlet —14— communicating with a feed hopper —15— into which the coal is placed by hand or otherwise so as to feed by gravity through a connecting chute —16— and inlet —14— into the inner circular grid —4—. It is desirable, however, to provide a mechanical feeding device for the coal and for this purpose I have provided an upwardly tapering feed screw —17— centrally in the apex of the hopper —15— and coacting with laterally adjustable valves —18—, the screw —17— being driven from the main shaft —3— through the medium of intermeshing gears —19— and a shaft —20— for the purpose of establishing a positive feed and also preventing the coal from becoming clogged in the hopper or chute while the valves —18— serve also to prevent excessive accumulation of the coal at the base of the screw and also regulate the amount of fuel fed by the screw so that such feed will be more uniform.

Each of the circular grids 4, 5 and 6 is made up of a series of axially projecting parallel bars spaced a suitable distance apart and secured at one end to the disk —1— and having their opposite ends provided with bearing members —21— consisting preferably of rollers connected to adjacent ends of the corresponding bars and riding upon suitable circular tracks —22— on the inner face of the disk —2—. The openings in the grids 4, 5 and 6 gradually diminish in size, those in the grid —6— being comparatively fine and tend to hold back the previously comminuted particles until reduced to the desired powdered form by the hammers —9—. These hammers are arranged in sets of, in this instance, two each, those of each set being pivotally mounted at one end upon supporting pins or studs —23— which in turn

2
are rigidly secured to the disk —2—, the studs —23— being arranged in concentric rows a sufficient distance apart to permit free swinging movement of the hammers, 5 said hammers of each set being also spaced apart side by side from each other and from the disks —1— and —2— by spacing sleeves —24— which encircle the corresponding bolts. The free ends of the hammers are 10 elongated laterally and travel in close proximity to the inner faces of their respective grids with which they coact in effecting the pulverizing of the coal.

Rigidly secured to the periphery of the 15 disk —2— are a series of fan blades —26— projecting radially beyond the periphery of the outer grid —6— and serving to collect and expel the powdered coal from the interior of the case through a suitable discharge 20 opening —27— in one side of the case —10— and preferably tangential to the path of movement of the blades —6—, the outlet being adapted to be connected directly to a 25 burner or combustion chamber with which the pulverizer may be used.

As previously intimated this machine is adapted to feed its pulverized product directly into a furnace and it is found to be expedient to introduce a sufficient amount 30 of air into the pulverized coal to hold the powder practically in suspension so that the ignition may be more instantaneous and the combustion more complete and for this purpose I provide the coal feeding chute leading to the inlet of the machine with one or 35 more air inlets —30— through which an extra amount of air may be introduced to mix with the coal as the latter enters the first grid. The air and coal are therefore 40 agitated together and thoroughly mixed during the pulverizing process and inasmuch as the grids are interposed between the air and coal inlets and the outlet for the pulverized coal, it is apparent that the 45 entire mixture must emerge from the last grid in a thoroughly agitated and mixed condition to such an extent that the impalpable powder is held more or less in suspension and fed in this condition by the fan 50 blades directly into the furnace, thus preparing the fuel for quick ignition and more perfect combustion.

In operation the coal is placed by hand or otherwise in the hopper —17— and then 55 gravitates into the interior of the innermost grid —4—, the passage of the fuel being aided somewhat by suction produced by the operation of the fan —26—. Now by rotating the disks —1— and —2— in opposite 60 directions it is evident that the coal introduced into the innermost grid —4— will be ground into a more or less comminuted state by the action of the hammers —7— with the inner surface of said grid, until the particles of coal are sufficiently small to pass

through this grid and thence into the second grid —5— where a similar action takes place between the hammer —8— and grid —5—. The openings in the latter grid are somewhat smaller than those in the grid 70 —4— and therefore the particles of coal which may pass through the grid —5— will be somewhat smaller than those which have been previously passed through the grid —4—. This further pulverized coal passes 75 through the grid —5— and into the grid —6— where it is further reduced to a substantially powdered condition and in such condition drawn by suction of the fan through the interstices into the interior of the casing —10— and is then forced by the fan —26— through the outlet —27—.

By rotating the grids and hammers in opposite directions in the manner described, it is evident that the speed of travel of each is comparatively low or substantially one-half of what would be required if the grids were stationary and at the same time this speed is sufficiently high to cause the hammers —7— to assume a substantially radial 90 position by centrifugal force when free from resistance but under such resistance may readily yield thereby avoiding any liability of injury to either the hammers or grids.

What I claim is:

1. In a pulverizing machine, a plurality of concentric grids, a revoluble disk, a plurality of concentric rows of pivoted hammers in close proximity to the grids and mounted upon one face of said disk, and 100 radially projecting fans upon the periphery of said disk positioned outside of the path of movement of the hammers.

2. In a pulverizing machine, a rotary circular grid and means for rotating it, a series 105 of pivoted hammers having their free ends disposed in close proximity to the inner face of the grid and means for rotating the hammers in a direction opposite to that of the grid, a track positioned adjacent said hammers, rollers carried by said grid adapted for bearing upon a track, radially and outwardly-projecting fans positioned adjacent said hammers, and an inclosing case for the grid hammers and fan blades and said case 115 provided with an inlet and an outlet.

3. A coal pulverizer comprising an inclosing case having an inlet and an outlet, a rotary circular grid, a concentric series of hammers, a rotatable support for the hammers, a fan upon said support, said support and grid mounted within the inclosing case, and means for rotating said grid and support.

4. In a coal pulverizing machine, a plurality of rotary concentric grids and a support therefor, a rotary hammer support having a plurality of circular rows of hammers pivotally mounted thereon and operated 125 centrifugally into grinding coaction with 130

the inner faces of their respective grids, means for rotating said supports in opposite directions, fan blades mounted on one of the supports, and an inclosing case for the grids, 5 hammers and fan blades, having an inlet adjacent the grids and an outlet adjacent to the fan blades.

In witness whereof I have hereunto set my hand on this 17th day of October 1910.

GEORGE R. MITCHELL.
